UNITED STATES PATENT OFFICE.

AUSTIN BURT, OF BLACK RIVER FALLS, WISCONSIN, ASSIGNOR OF ONE-HALF
TO HORACE E. BURT, OF SAME PLACE.

TEMPORARY BINDER.

SPECIFICATION forming part of Letters Patent No. 476,363, dated June 7, 1892.

Application filed September 16, 1890. Serial No. 365,166. (No model.)

To all whom it may concern:

Be it known that I, AUSTIN BURT, a citizen of the United States, residing at Black River Falls, in the county of Jackson and State of Wisconsin, have invented a new and useful 5 Temporary Binder, of which the following is a specification.

The invention relates to improvements in temporary binders.

10 The object of the present invention is to provide a simple and inexpensive temporary binder adapted to be applied to a pamphlet, magazine, paper-covered book, circular, or a collection of papers, whether previously bound 15 or not, to protect and hold the same together for a longer or shorter time, and which may be quickly removed therefrom and applied to others.

The invention consists in the construction 20 and novel combination and arrangement of parts hereinafter fully described, illustrated in the accompanying drawings, and pointed out in the claim hereto appended.

In the drawings, Figure 1 is a perspective 25 view of a temporary binder embodying the invention and shown applied to a book, the latter being partly broken away. Fig. 2 is an end view. Fig. 3 is a plan view.

Referring to the accompanying drawings, 30 1 designates a temporary binder and shield or protector constructed of a strip of tin or other sheet metal which is pliable and is cut the desired size and has its longitudinal edges rolled over wires 2 of suitable size, so 35 as to encircle the same and to form round beads 3, said wires 2 remaining therein to stiffen the beads, although the effect is substantially the same when the wires are withdrawn and as has been employed in the previous art; but by inserting the wires set forth 40 and causing them to partake of the end flare a more durable construction is provided, in that crushing of the heads is prevented, especially at the flared ends, and a greater resisting resiliency or binding is obtained. In 45 Fig. 1 of the accompanying drawings the wires are removed and in Fig. 2 the wires are left in the round beads to strengthen the same. The sheet-metal strip is then bent to form a 50 circular or tubular back 4, which has the longitudinal opening 5 between the beads 3, and

the said opening is adapted to be varied in size by bending the back with the fingers to suit the books, pamphlets, or similar papers to be bound or protected. The longitudinal 55 beads 3, as will be seen, project at their inner edges into the circle, which would be formed by the back 4 if continued, and hence when this back is opened to or even beyond a **U** shape the inner sides of the beads will still 60 bear on the papers. Obviously such would not be the case if the beads were omitted. Moreover, by having such beads cylindrical the spring force of the back will bear them against the papers along two narrow lines 65 only and will clip or bite the papers with a force that will prevent slipping, yet not produce scratching or tearing. The said beads are bent near each end of the binder and slightly diverge at 6 to form somewhat flaring mouths to enable the protector to be readily slipped on a magazine, paper-covered book, or the like without liability of injuring the cover.

In use the temporary binder is first adjust- 70 ed to the thickness of the magazines, periodicals, papers, books, or the like by pressing the beads 3 together or separating them, and the back edge or margin of the same is entered at the end of the binder and drawn longitudinally and evenly between the beads as far as desired, whereby the same is grasped firmly enough to be retained and protected for any length of time, keeping the leaves from being separated or injured while the 85 magazine, paper-covered books, or other papers are in use.

What I claim is—

A temporary binder consisting of a piece of resilient metal bent into **U** shape and having 90 cylindrical-rolled edges diverging from each other at each end to form flaring mouths and wire rods inclosed within said rolled edges, substantially as described.

In testimony that I claim the foregoing as 95 my own I have hereto affixed my signature in presence of two witnesses.

AUSTIN BURT.
